UNITED STATES PATENT OFFICE

JOHN FLAVELL PEAKE, OF LEICESTER, ENGLAND, ASSIGNOR TO UNITED SHOE MACHINERY CORPORATION, OF PATERSON, NEW JERSEY, A CORPORATION OF NEW JERSEY

MACHINE FOR OPERATING UPON SHOE STIFFENERS

Application filed November 20, 1928, Serial No. 320,554, and in Great Britain December 23, 1927.

This invention relates to machines for operating upon blanks to impart to them a desired shape and is herein illustrated as embodied in a machine for skiving counters for use in the manufacture of boots and shoes.

In the manufacture of counters it is customary to die out a blank of the proper outline from suitable sheet material, such as leather or fiberboard, and to bevel its margin by holding the blank in a suitably shaped matrix and moving the matrix in a path to feed the blank to a tool, such as a knife, which removes those portions of the blank projecting above the matrix. In order to speed up machines of this type it is desirable that the blanks should automatically be delivered one by one to the matrix while the matrix is moving.

According to one feature of the invention a magazine in which the blanks are stacked and from which they are delivered to the feeding means partakes intermittently of the movement of the feeding means. In the illustrated machine there is provided a rotary disk knife, a rotary table having in its otherwise flat upper face a plurality of matrices, and a magazine for a stack of blanks located above the table. As a matrix moves into position beneath the magazine, a blank is delivered into the matrix and held there by suction until the matrix has fed the blank past the knife which skives it to a shape determined by the shape of the matrix. In order to ensure that the magazine and the matrix shall be in register long enough to permit ready and accurate placing of a blank in the matrix, the magazine is engaged by the rotary table and moved with it for a short distance every time a matrix comes into position beneath the magazine.

It is desirable that each skived blank should be removed from its matrix and discharged from the machine. To this end, and in accordance with another feature of the invention, such a discharging means is provided. In the illustrated machine this takes the form of a hollow swinging arm which is adapted to engage the blank by suction, to swing away from the machine and to drop the blank into a suitable receptacle.

These and other features of the invention including certain details of construction and combinations of parts will be described as embodied in an illustrated machine and pointed out in the appended claims.

In the accompanying drawings,

Fig. 1 is a front elevation, partly in section, showing part of a machine embodying the invention;

Fig. 2 is a plan view of the machine;

Fig. 3 is a section on the line 3—3 in Fig. 2;

Fig. 4 is a plan view of the top of the casting upon which the table rotates, and

Fig. 5 is a vertical longitudinal section through the machine.

The machine comprises a rotary table 1 carrying two diametrically opposite blank receiving depressions or matrices 2 of the shape and size which it is desired that the finished stiffeners shall have. The blanks to be operated upon are carried in a magazine which comprises angle bars 3 and 4 arranged to position the corners of the blanks and bars 5 and 6 engaging the front of the blanks. The bars 5 and 6 have projecting from them arms 7 and 8 which are clamped by bolts 9 to the bars 3 and 4 and are adjustable about the bolts. The bars 3 and 4 are clamped by bolts 10, about which they are adjustable, to slides 11 and 12. The slides 11 and 12 may be adjusted lengthwise in brackets 13 and 14 and clamped by screws 15. The brackets 13, 14 are mounted on spindles 16, 17 on which they may be adjusted vertically by nuts 18. The brackets 13, 14 may also be swung about the spindles 16, 17 and locked in position by a bolt 19 which passes through arcuate slots in plates 20, 21 fixed to the brackets. These adjustments allow the magazine to be adjusted to suit the size or shape of the blanks and also allow it to be adjusted to position the blanks correctly over the matrices. The spindles 16, 17 are fixed in one arm of a bell-crank lever 22 which, as will presently be explained, is arranged to swing about the shaft 95 on which the table 1 is mounted. The lower ends of the bars 3 and 5 are set down as close as possible to the table while the lower ends of the bars 4 and 6 are set so that there is just room between them and the table

for the passage of the lowermost blank in the magazine. To prevent the second blank from the bottom of magazine from being withdrawn with the first blank the bars 4 and 6 have movably mounted on them auxiliary bars or gates 37, 38. The gate 37 is pivoted at 139, 139 to arms 39, 39 projecting from the bar 4 and is urged toward the bar by a spring 40 surrounding a stud 140 fixed in the bar 4 and bearing against the gate 37 and the head of the stud. The gate 38 is connected to the bar 6 by a pin 41 in the bar which is a loose fit in a hole in the gate and by a stud 143 fixed in the bar 6 and passing loosely through a hole in the gate 38. A spring 42 surrounds the stud 143 and bears against the gate 38 and a head on the stud. The spring urges the gate 38 toward the bar 6. The lower ends of the gates 37, 38 are set as close as possible to the table, and the springs 40, 42 allow the gates to yield by the engagement of the lowermost blank with them as it is withdrawn from the magazine. The lower end of the gate 37 is swung by the blank about the pivots 139 outwardly and upwardly away from the magazine; and the lower end of the gate 38 is similarly swung, the loose fit of the pin 41 and the stud 143 in their respective holes permitting the slight swinging movement which is necessary.

The bell-crank lever 22, upon the short arm of which the magazine for the blanks is mounted, is adapted to be engaged and rotated by the table 1 for a short distance whenever one of the matrices moves into position beneath the magazine. To this end the long arm of the bell-crank lever 22 carries a pawl 23 which, as the table rotates, is engaged by one or other of two lugs 24, 25 on the table. One of the lugs 24 or 25 engages the pawl 23 just as one of the matrices 2 moves into position beneath the magazine and carries the bell-crank lever 22 and magazine around with the table until a tail 26 on the pawl engages a pin 27 projecting from the frame of the machine, and the pawl is disengaged from the lug. The movement of the magazine with the table provides time for the transfer of the lowermost blank in the magazine to the matrix and ensures the correct position of the blank in the matrix. Each matrix 2 has in it a plurality of perforations 60; and when a matrix has arrived beneath the magazine and the matrix and magazine have moved a short distance together, the holes in the matrix are automatically connected to a suction pump (not shown) whereby the lowermost blank of the stack is drawn firmly down into the matrix and held therein while the matrix moves on away from the magazine beneath a rotary disk knife 35 which skives the blank. The suction is maintained until the skived blank arrives at a delivery station at the rear of the machine when the suction in the matrix is released and the skived blank

is picked up by a suction arm 50 and delivered from the machine. When the pawl 23 is released, the bell-crank lever is pulled back by springs 28 connected to a pin 29 in the lever and to pins 30 fixed in a member 31 carried by the machine frame. The springs 28 are so arranged that, when the pawl is released, they not only pull the magazine back again away from the blank which is held in the matrix by suction but cause the magazine to oscillate for a short time about the pivot of the bell-crank lever. This oscillation effects a shaking or settling down of the blanks in the magazine. A rubber block 32 is fixed on the frame and acts as a buffer for the bell-crank lever during its return movement. A hand lever 33 is pivoted on the frame and carries a block 34. By moving the lever about its pivot the block may be caused to engage the tail 26 of the pawl and swing the pawl out of the path of the lugs 24, 25 so that the swinging movement of the magazine may be stopped, for example for the purpose of loading the magazine, although the table continues to rotate.

The rotary disk knife 35 is carried on the lower end of a shaft 43 which is rotatably mounted in a bracket fixed on the frame of the machine and is continuously driven. The shaft above the knife has fixed to it a disk 44 between which and a collar 45 on the shaft extend rods 46 arranged to throw out the skivings. The knife shaft is tilted in relation to the upper surface of the table so that the portion of the edge of the knife which skives the blank is close to the surface of the table while its opposite portion is slightly raised. The knife is fixed against vertical movement, and the table may be adjusted vertically to determine the thickness to which the edge of the blank is skived. A grinding wheel 36 is provided, and during the operation of the machine the knife is being ground continuously.

As the blank in the matrix approaches the skiving knife it passes under a presser arrangement consisting of a number of presser members 47 pivoted at 48 to an arm 49 extending from the frame of the machine and each urged yieldingly independently, by suitable springs, about the pivot 48 down toward the table 1 so as to hold the blank down in front of the knife. To enable the blank to be held close to the edge of the knife at along a considerable part of said edge, the presser members present a curved front, when seen from above the curvature of which conforms to that of the periphery of the knife.

At the rear of the machine is the discharging device consisting of the tubular arm 50 (mentioned above) which is pivotally mounted at 51 on the machine frame and has a suction orifice at 52. An arm 53 integral with the tubular arm 50 is connected by a link 54 to an arm 55 pivoted at 56 to the frame; and

the arm 55 has on it a curved finger 57 which is engaged alternately by rolls 58 carried on the under side of the table 1 to swing the arm 50 outward, the arm being returned by a spring (not shown). The skived blank is thereby picked up from the matrix and held against the orifice 52 while the arm 50 is swung outward by the action of that roll 58 which engages the finger 57. Just as the arm 50 reaches its outermost position the suction in the arm is cut off, and the blank falls into a receptacle (not shown) at the rear of the machine.

The suction is controlled by an arm 61 fixed 15 on a shaft 62, mounted beneath the rotary table in bearings in the frame, on which shaft is also fixed an arm 63 having connected to it a rod 64. The arm 61 is engaged alternately by the rolls 58 as the table rotates, and the 20 rod 64 is connected to a slide valve 80 (Fig.

4) which allows the suction to have effect either on the matrix at the loading station or on the discharging device. As the matrices approach respectively the loading and the 25 discharge stations, that one of the rolls 58 which is then beneath the magazine engages the arm 61 and moves the rod 64 downward. Such downward movement of the rod, through the valve, causes suction to be applied to the discharging device which thereupon picks up the skived blank which is then beneath it. When the roll 58 leaves the arm 61 and the rod 64 moves upward, suction is 30 withdrawn from the discharging device and is applied to the matrix at the loading station; and for a short time thereafter the table and magazine travel together, as has been explained, and the lowermost blank in the magazine is pulled down into the matrix.

40 When the suction is thus applied to the matrix, it is cut off from the discharging device; but the vacuum created in said device holds the blank against the suction orifice until the arm 50 is swung fully out, whereupon the 45 vacuum is broken through a port indicated at 65. The suction is maintained at the matrix which is beneath the magazine until the matrix nearly reaches the discharging station when it is cut off by the depression of the 50 rod 64 by the other roll 58; and the vacuum is broken by a port in the table below the matrix coming into alignment with a port which is open to the atmosphere.

55 When the swinging movement of the magazine is prevented from taking place by manipulation of the hand lever 33, the feeding of the blanks is also stopped because, as hereinbefore stated, the suction is not applied to the matrix until the matrix and magazine 60 have moved a short distance together so that, if movement of the magazine is prevented, some of the holes in the matrix will have passed beyond the lowermost blank when the suction comes on, so that the suction is then ineffective to draw the blank into the ma-

trix; and the matrix, therefore, continues its travel empty.

Referring now more particularly to Figs. 5 and 6, the table 1 is fast to the upright shaft 75 about which the bell-crank lever 22 is pivoted, the shaft being rotatable in but held from longitudinal movement with respect to a casting 76 which may be adjusted vertically by turning a hand wheel 77. This hand wheel is fast to a short horizontal shaft rotatably mounted in the frame of the machine and having at one end a bevel gear 78 which meshes with a bevel gear 79 on the lower end of a short vertical shaft which is threaded into the casting 76. This latter short shaft is 75 rotatably mounted in the frame of the machine but held from longitudinal movement. The shaft 75 is rotated continuously through a gear 93 which is fast to the lower end of the shaft.

80 Turning now to the control of the suction, the slide valve 80, which is pivoted to the lower end of the rod 64, is adapted to connect the port 81 of a suction pump either with a port 82 which leads to a locality beneath the magazine or with a port 83 which leads to the discharge arm 50. A coiled spring 85, the upper end of which engages the under side of a head on the rod 64 and the lower end of which rests upon a stationary part of the machine, normally holds the slide valve 80 in its upper position in which the port 81 of the suction pump is connected to the port 82. Thus when either of the rolls 58 is in contact with the arm 61, the suction pump is 100 connected to the discharge arm 50, and, when neither of the rolls is in contact with the arm 61, the suction pump is connected to the port 82 and hence to one of the matrices if one of them is at that time beneath the magazine. 105 The port 82 leads to an arcuate groove 87 formed in the top of the casting 76; and this groove communicates alternately, as the table 1 rotates, with ports 88, 89 in the table which lead respectively to the matrices 2. 110

With the parts in the positions shown, the slide valve 80 has been moved into a position in which the port 81 of the suction pump is connected to the discharge arm 50. As the table rotates, in a counterclockwise direction 115 as viewed in Fig. 1, the magazine travels for a time with it; and, as soon as the roll 58 at the loading station leaves the arm 61, the slide valve is moved to connect the port 81 to the port 82, whereupon the lowermost blank is 120 drawn down into the matrix which is then beneath the magazine. When the slide valve is moved to connect the port 81 to the port 82, the suction is cut off from the discharge arm 50, but the vacuum in the arm 50 holds 125 the stiffener which has been picked up by the arm until the vacuum is broken by admission of air through the small port 65. As the table continues to rotate, the suction is maintained in the matrix, which has just received a 130

stiffener blank, by reason of the arcuate groove 87 until after the blank has been skived. The suction is cut off when the end of the arcuate groove 87 is reached and the port 88 passes out of register with said groove. More or less of a vacuum is present in the port 88, however, until it moves into communication with a port 90 in the casting 76 which leads to the atmosphere whereupon the skived blank in the matrix is free to be picked up by the discharge arm 50. A portion of each of the ports 82 and 83 consists of flexible tubing so as to permit vertical adjustment of the casting 76.

15 Although the invention has been set forth as embodied in a particular machine, it should be understood that the invention is not limited in the scope of its application to the particular machine which has been shown 20 and described.

Having thus described the invention, what I claim as new and desire to secure by Letters Patent of the United States is:—

1. A machine of the class described having, 25 in combination, a tool for operating upon a blank, moving means for feeding a blank in a direction to carry it to and past the tool, a magazine for a stack of blanks located in position to deliver blanks one by one to the feeding means, and means for causing the magazine to move at intervals with the feeding means in the direction named.

2. A machine of the class described having, 35 in combination, a tool for operating upon a blank, moving means including a matrix for feeding a blank in a direction to carry it to and past the tool, a normally stationary magazine for a stack of blanks located in position to deliver blanks one by one to the matrix, and means for causing the magazine to move at intervals with the feeding means in the direction named.

3. A machine of the class described having, 45 in combination, a tool for operating upon a blank, a rotary table for feeding a blank to the tool, a magazine for a stack of blanks located in position to deliver blanks one by one to the table, and means for causing the magazine to move at intervals with the table 50 in the direction of its rotation.

4. A machine of the class described having, 55 in combination, a tool for operating upon a blank, a rotary table having a matrix for feeding a blank to the tool, a magazine for a stack of blanks located in position to deliver blanks one by one to the matrix, and means for causing the magazine to move at intervals with the matrix in the direction of its rotation.

60 5. A machine of the class described having, 65 in combination, a tool for operating upon a blank, continuously driven means for feeding a blank to the tool, a magazine movable back and forth in a path corresponding to a portion of the path of the feeding means, and

means for intermittently moving the magazine with the feeding means.

6. A machine of the class described having, 70 in combination, a tool for operating upon a blank, continuously driven means including a matrix for feeding a blank to the tool, a magazine movable back and forth in a path corresponding to a portion of the path of the feeding means and adapted to deliver blanks one by one to the matrix, and means for intermittently moving the magazine with the feeding means.

7. A machine of the class described having, 75 in combination, a skiving knife, a table located beneath the knife and having a matrix to receive a blank, means for rotating the table continuously, a magazine for a stack of blanks located above the path of the moving matrix and adapted to deliver blanks one by one to the matrix, and means for moving the magazine at intervals with the table.

8. A machine of the class described having, 80 in combination, a skiving knife, a table located beneath the knife and having a matrix to receive a blank, means for rotating the table continuously, a magazine for a stack of blanks beneath which the matrix passes so that the lowermost blank of the stack may be delivered into the matrix, means for moving the magazine for a short distance to maintain it above the moving matrix, and suction means operating upon the blank through the matrix.

9. A machine of the class described having, 90 in combination, a tool for operating upon a blank, a matrix, suction means for holding the blank in the matrix, means for moving the matrix to cause the blank to be operated upon by the tool, means for thereafter cutting off the suction from the matrix, and means 100 for removing the blank from the matrix and discharging it from the machine.

10. A machine of the class described having, 105 in combination, a skiving knife, a rotary table having a plurality of matrices adapted to receive blanks, a magazine for a stack of blanks from which the blanks are delivered one by one into the matrices, said magazine being located in front of the knife, a discharge member located in the rear of the 110 knife, and means for applying suction to the matrix when it is beneath the magazine, for cutting off the suction after the blank has been skived and for thereafter applying suction to the discharge member.

11. A machine of the class described having, 115 in combination, a tool for operating upon a shoe part, a feed member, means for moving the feed member in a direction and to an extent to carry the shoe part to and past the tool, a magazine for shoe parts, and means for moving the magazine at intervals in the same direction.

12. A machine of the class described having, 120 in combination, a tool for operating upon a

5 a shoe part, a feed member, means for moving the feed member in a direction to carry the shoe part to and past the tool, a magazine for shoe parts, means for moving the magazine at intervals in the same direction, and means operating during the movement of the magazine to transfer a shoe part from the magazine to the feed member.

10 13. A machine of the class described having, in combination, a tool for operating upon a shoe part, a feed member, means for moving the feed member in a direction to carry the shoe part to and past the tool, a magazine for shoe parts normally stationary but capable of movement in the same direction as the feed member, and means for connecting the magazine with the feed member at intervals and for disconnecting it therefrom.

15 14. A machine of the class described having, in combination, a tool for operating upon a shoe part, a feed member, means for moving the feed member in a direction to carry the shoe part to and past the tool, a magazine for shoe parts normally stationary but capable of movement in the same direction as the feed member, means for connecting the magazine with the feed member at intervals and for disconnecting it therefrom, and means operating while the magazine is connected to 20 and moving with the feed member in the direction stated, for transferring a shoe part from the magazine to the feed member.

25 In testimony whereof I have signed my name to this specification.

30 35 JOHN FLAVELL PEAKE.
